UNITED STATES PATENT OFFICE.

JEFFREY T. FERRES, OF ANDERSON, INDIANA, ASSIGNOR TO J. W. SEFTON MANUFACTURING COMPANY, OF ANDERSON, INDIANA, A CORPORATION OF INDIANA.

PACKING OR SHIPPING BOX.

No. 881,567.

Specification of Letters Patent. Patented March 10, 1908.

Application filed February 27, 1905. Serial No. 247,586.

To all whom it may concern:

Be it known that I, JEFFREY T. FERRES, a citizen of the United States, residing at Anderson, Madison county, Indiana, have 5 invented certain new and useful Improvements in Packing or Shipping Boxes, of which the following is a specification.

My invention relates to packing or shipping boxes made from paper board, by preference from what is commonly known as double-faced corrugated paper board, and the object thereof is to produce a novel and efficient form and construction of a box of this character which is particularly useful 15 for the packaging and shipping of such articles as fruit, although my box will be found useful for other purposes.

The various features of advantage and utility of my novel form of box will be apparent from the description hereinafter given.

In the drawings, Figure 1 is a plan view of a blank, from which the bottom, top and one of the side walls is formed; Fig. 2 is plan view of a blank from which the other side 25 wall and the two end walls of my box are formed; Fig. 3 a perspective illustrating my box in complete form with the top or lid thrown open; Fig. 4 a perspective of the box in assembled and closed form; Fig. 5 30 a plan view of the box in knock-down form; Figs. 6, 7, and 8 plan views of blanks for a modified form of box, and Figs. 9 and 10 views similar to Figs. 3 and 4 but illustrating said modified form of box.

It will be understood that my box may be 35 made of any suitable size and dimensions for the particular kind of goods to be packaged and shipped therein, but in the present instance the particular forms of boxes illustrated herein are rectangular and also oblong in cross section.

Referring to the form of box illustrated in Figs. 1 to 5, such box is made in two parts or sections, one section being illustrated by 45 the blank in Fig. 1 and the other section by the blank in Fig. 2. The first mentioned section consists of the bottom 1, the top 2, with one of the side walls 3 intermediate thereof and hinged thereto. In addition the 50 top is provided with lateral extensions or flaps 1^a on its opposite ends and also with the extension or flap 1^b extending from the other free edge thereof and adapted to be secured by the tapes 8, or otherwise, to the

extensions 1^a. The top or closure 2 is 55 similarly provided with the lateral flaps or extensions 2^a and with an end extension or flap 2^b. The side wall 3 is provided with lateral extensions or flaps 3^a, together with a second, outer score line 3^b, in addition to 60 and parallel with the score line near opposite sides of the blank to provide for the hinging of the flaps or extensions 1^a, 2^a, and 3^a, to the bottom, top and side walls respectively. For a purpose hereinafter made 65 apparent, the distance between this additional score line 3^b and the regular score line indicated by 3^c is substantially equal to the thickness of the board, from which the box is made, but more particularly the thickness 70 of the end walls, inasmuch as such double scoring is for the purpose of accommodating the thickness of such particular parts of the box.

The second section of the box or receptacle is also by preference made from a single blank which is transversely scored as indicated in Fig. 2 to form the other side wall 4, corresponding to the side wall 3 and also to 75 form the two similar end walls 5 hinged to the side wall 4, but arranged in the present instance, at opposite ends of the blank. As indicated, each of the end walls is provided with similar slots, 5^a entering from the top and bottom edges of the side walls and in the 80 present instance, and preferably, though not necessarily, arranged at the middle vertical line of each end wall. In fact, these slots may be at any point in the end walls 5. The 85 purpose of these slots is to receive the flaps 1^a and 2^a of the bottom and top respectively and 90 in a manner hereinafter explained, and to this end such slots are made of a depth substantially equal to the width of such extensions or flaps.

The end walls 5 and 6 are secured to the flaps or extensions 3^a of the side wall 3 in suitable manner, but preferably by means of the staples 7, as indicated in Figs. 3 and 4, but by reason of the double scoring 3^b the inner surfaces of these end walls lie in a plane 100 co-incident with the outer surfaces of the flaps or extensions 1^a and 2^a, so that the latter may readily fold or take their position within the end walls without distending the 105 latter, in the manner indicated in Fig. 4.

In setting up the box for use, the body portion thereof which has been in collapsed or

knocked-down form is distended as seen in Fig. 3 and the bottom 1 is brought to the position as indicated in said figure, with the extensions 1^a thereof at their inner ends fitting within the end walls and entering the lower set of slots 5^a and then taking their position for the remainder of their length—that is to the front corner of the box—on the outside of the end walls in a manner clearly indicated in Figs. 3 and 4. After the box or receptacle has received its articles to be shipped therein, the top or closure 2 is swung down in position with the inner end of its flaps 2^a positioned within the end walls and passing through the slot, taking their position for the remainder of their length on the outside of the end walls in the same manner as the bottom flaps 1^a, all as clearly indicated in Fig. 4. In this manner a simple and inexpensive packing box having great strength and rigidity is produced, the extensions or flaps of the top and bottom covers or closures firmly securing the body portion of the box and the lateral flaps particularly re-inforcing and strengthening the end walls and being themselves held in proper bracing or re-inforcing position by the end walls themselves by reason of the interlocking connection between such flaps and the end walls. Moreover, my packing box possesses the advantage of being readily collapsed or knocked down so that it may be conveniently shipped in flat form. It will be understood that at the factory the section of the box illustrated in Fig. 2 is secured to the section shown in Fig. 1 and that such second section is collapsed flat upon the side wall 3 in the manner indicated in Fig. 5. These boxes are shipped to the consumer or user in the flat form shown in said Fig. 5 and the same are packed in pairs, two of such boxes in this flattened form being reversed and inserted or nested in each other, so as to take up a minimum amount of space. It will also be understood that the extensions 1^b and 2^b are secured to the other extensions 1^b and 2^b respectively in suitable manner, as by means of the tapes 8.

Now referring to the modified form of box illustrated in Figs. 6 to 11, this form is substantially the same as that hereinbefore described, with the exception that the box, instead of being made in two parts or from two single blanks, is made in four parts or sections illustrated in Figs. 6, 7 and 8, the fourth member or section being a duplicate of Fig. 7. Figs. 6 and 8 illustrate the top 9 and bottom 10 with the end extensions or flaps 9^a and 10^a respectively and also the side extensions or flaps 9^b and 10^b. By preference, the extensions 9^b and 10^b are secured to the ends of their respective extensions 9^a and 10^a in suitable manner, as by means of the tapes 11. The body of this modified form of box is made in two similar

parts or sections which may both be illustrated by Fig. 7, each section consisting of a side wall 12 and an end wall 13, each side wall having a pasting strip 12^a to enable it to be secured to an adjacent end wall 13, as indicated in Fig. 9. Each end wall is provided with similar slots 13^a entering from opposite edges—that is from the top and bottom edges and corresponding to the slots 5^a in the form of box first described. By preference, both of the closures are hinged to the rear side wall, the top being provided with a pasting flap 9^c for hinging it to such rear side wall along its upper edge and the bottom 10 being provided with a similar pasting strip 10^c for hinging it to the lower edge of the same rear side wall. The box is set up for use in the same manner as the box hereinbefore described and when in position ready for use assumes the form illustrated in Fig. 9 and when filled and ready for shipment assumes the position illustrated in Fig. 10. This modified form of box, as well as the preferred form illustrated in Figs. 1 to 5, may be provided with projecting pieces or strips 14 on the outer faces of the top and bottom in order to distance or space the box away from the floor or away from a box placed or stacked thereon, in order to provide for ventilation between the boxes or between the boxes and the floor, which may be found necessary or desirable in the shipping of some kinds of fruit. Moreover, if desired and as shown in respect to the modified form of box, the closures may be provided with holes or openings for ventilating the interior.

Either form of the packing box illustrated herein may be tied or sealed in any suitable manner as by means of cords tied around the box, more particularly to keep the top and bottom closures in place. In respect to the modified form of construction, however, I have illustrated a fastening means composed of wires, although the ordinary cords are sufficient for the purpose. As shown in Figs. 9 and 10, I provide the top and bottom preferably at a central point at their free ends or sides with a wire 16, whose outer ends are secured thereto, preferably by passing them through one of the pieces or blocks 14 and fastening them to a button 17 or the like, as clearly shown in Fig. 10. After the closures are brought securely together the two wires are looped over each other and the free ends are passed underneath the extensions or flaps 9^b and 10^b, respectively.

I claim:

1. A packing box or receptacle comprising side and end walls, two opposite walls being provided with opposite vertical slots entering from their top and bottom edges and scores connecting said slots running across such walls to enable them to be collapsed for shipping, and a closure provided

with extensions on two opposite sides adapted to be received in and interlock with said slots; substantially as described.

2. A packing box or receptacle comprising a body portion consisting of sides hinged to each other, and closures therefor provided with side extensions, two of the opposite sides having slots entering from their top and bottom edges, said slots being connected by scores and arranged to receive the extensions of the closures; substantially as described.

3. A packing box or receptacle comprising a body portion consisting of sides hinged to each other, and closures therefor provided with side extensions, and hinged to the top and bottom of such body portion of the box, two of the opposite sides of said body portion having slots connected by scores and arranged to receive and interlock with the extensions of the closures; substantially as described.

4. A packing box or receptacle comprising a body portion consisting of side and end walls hinged to each other, the end walls having slots connected by scores extending inwardly from their opposite edges, and top and bottom closures hinged to one of the side walls and having extensions or flaps entering the slots when the box is assembled; substantially as described.

5. A packing box or receptacle comprising a body portion consisting of side and end walls hinged to each other, and top and bottom closures hinged to one of the side walls and having extensions on two of its opposite edges corresponding with the ends of the box, the end walls of the box having at their middle line slots connected by scores, said slots entering from opposite edges and substantially equaling in length the width of said extensions, and receiving the extensions; substantially as described.

6. A packing box or receptacle made in two parts or sections, one section comprising one side wall and two end walls which end walls are provided with transverse slots entering from their top and bottom edges said slots being connected by scores, and the other section consisting of the top and bottom closures with an intermediate portion hinged to the closure and forming the second side wall of the box, said closures having on

two opposite sides flaps or extensions arranged to be received by said slots intermediate their length; substantially as described.

7. A packing box or receptacle made in two parts or sections, one section comprising one side wall and two end walls which end walls are provided with transverse slots entering from their top and bottom edges, and the other section consisting of the top and bottom closures with an intermediate portion hinged to the closure and forming the second side wall of the box, said closures having on two opposite sides flaps or extensions arranged to be received by said slots intermediate their length, and said second side wall of the box being provided with extensions having scores parallel to the hinge lines of the side flaps of the closure and distant outwardly therefrom the thickness of the material of the box, the end walls being secured to said extensions along said outer score line to permit the extensions of the closures to freely enter within the end walls of the box, as far as their slots; substantially as described.

8. A packing box or receptacle comprising two side walls and two end walls hinged together, the end walls having opposite slots connected by scores, and closures hinged to one of the side walls and having extensions or flaps adapted to be received by the slots; substantially as described.

9. A packing box or receptacle made in two parts or sections, one section comprising one side wall and two end walls which end walls are provided with transverse slots entering from their top and bottom edges, and the other section consisting of the top and bottom closures with an intermediate portion hinged to the closure and forming the second side wall of the box, said closures having on two opposite sides flaps or extensions arranged to be received by said slots intermediate their length, and the end walls having scores connecting their respective slots to enable such end walls to fold inwardly and collapse for shipping in knock-down condition; substantially as described.
